UNITED STATES PATENT OFFICE.

WILLIAM M. FOWLER, OF SOUND BEACH, CONNECTICUT.

RECEPTACLE SUPPORT FOR FILLING MACHINES.

Application filed November 23, 1920. Serial No. 425,973.

To all whom it may concern:

Be it known that I, WILLIAM M. FOWLER, a citizen of the United States, and resident of Sound Beach, in the county of Fairfield 5 and State of Connecticut, have invented a new and useful Improvement in Receptacle Supports for Filling Machines, of which the following is a specification.

The object of my invention is to provide 10 means whereby receptacles of different widths may be alined and properly supported without changing their position laterally with respect to their filling nozzles, thus eliminating the necessity of shifting the filling nozzles to suit receptacles of different 15 widths.

My invention includes generally one or 20 more pairs of parallel side members, one or more pairs of parallel bottom members, and means for varying the distance between the side members and between the bottom members of each pair to suit receptacles of different widths.

My invention more particularly includes 25 one or more series of rock levers to which the side and bottom members are connected, means being provided for rocking each series of levers to move the parallel side members and bottom members toward and 30 away from a median plane so as to properly aline and support the receptacles.

A practical embodiment of my invention is represented in the accompanying drawing, in which,

35 Fig. 1 represents in top plan so much of a receptacle support for filling machines as will give a clear understanding of my invention, the pairs of side and bottom members being shown in full lines in position to suit receptacles of a smaller diameter 40 and in dotted lines to suit receptacles of a larger diameter.

Fig. 2 represents an end view of the parts shown in Fig. 1.

45 Fig. 3 represents a section taken in the plane of the line III—III of Fig. 1.

The rigid crossbars of the support are 50 designated by 1, 2 and 3. I have represented three rock levers pivoted about midway between their ends to the crossbars 1, 2 and 3, the said rock levers being denoted by 4, 5 and 6. The parallel side members 7 and 8 of a pair are pivotally connected to the rock levers 4, 5 and 6 upon opposite 55 sides of the pivotal connection of said rock levers with the crossbars. The two parallel

bottom members 9 and 10 of a pair are also pivotally connected to the rock levers 4, 5 and 6 upon opposite sides of their pivotal connections with the crossbars 1, 2 and 3. 60

The side members 7 and 8 extend upwardly beyond the tops of the bottom members 9 and 10 so as to engage the opposite sides of the row of receptacles which are placed upon the bottom members. 65

There may be one or more series of rock levers and their pairs of side and bottom members. In the present instance I have shown three of these series which are operated simultaneously from a common rod 11 pivoted to extensions 12 of the rock lever 6. This rod 11 acts as a common means to move each pair of side members and each pair of bottom members toward and away from a median plane so as to adapt the side 75 and bottom members to receptacles of different widths, the side members serving to properly aline the receptacles of a predetermined width along the median plane which passes through the filling nozzle (not 80 shown herein) intended for that particular row of receptacles.

From the above description it will be seen that a very simple and effective means is provided for adapting the filling machine 85 rapidly and accurately to receptacles of different widths, without necessitating the shifting of the filling nozzles of the machine.

It is evident that various changes may be 90 made in the construction, form and arrangement of the several parts without departing from the spirit and scope of my invention; hence I do not wish to limit myself to the particular embodiment herein shown 95 and described, but—

What I claim is:—

1. A receptacle support for filling machines including a pair of parallel side members, bottom members parallel to the side members, and means for varying the distance between the side members and between the bottom members to aline and properly support receptacles of different widths. 100

2. A receptacle support for filling machines including a pair of parallel side members, bottom members parallel to the side members, and means for moving the side and bottom members toward and away from a median plane to aline and properly support receptacles of different widths. 105

3. A receptacle support for filling ma-

chines including a pair of parallel side members, parallel bottom members, a series of rock levers connecting the side members and bottom members, and a common means for 5 rocking said levers to move the side and bottom members toward and away from a median plane to aline and properly support receptacles of different widths.

4. A receptacle support for filling machines including a plurality of pairs of parallel side members, a plurality of sets of parallel bottom members, and means for varying the distance between the side members of each pair and between their bottom 15 members to aline and properly support receptacles of different widths.

5. A receptacle support for filling machines including a plurality of pairs of parallel side members, a plurality of sets 20 of bottom members, and a common means

for moving the side members of each pair and their bottom members toward and away from a median plane to aline and properly support receptacles of different widths.

6. A receptacle support for filling machines including a plurality of pairs of parallel side members, a plurality of sets of parallel bottom members, a plurality of series of rock levers connecting the side and bottom members and a common means for 25 30 rocking all of the series of rock levers to move their side and bottom members toward and away from a median plane to aline and properly support receptacles of different widths.

In testimony, that I claim the foregoing as my invention, I have signed my name this eighteenth day of November 1920.

WILLIAM M. FOWLER.
